UNITED STATES PATENT OFFICE.

GUSTAF HJALMAR LINDSTRÖM, OF GOTENBORG, SWEDEN, ASSIGNEE TO AKTIE-BOLAGET PRINCEPS, OF GOTENBORG, SWEDEN, A CORPORATION OF SWEDEN.

PLATEN PRINTING-PRESS AND THE LIKE.

1,219,119.

Specification of Letters Patent. Patented Mar. 13, 1917.

Application filed December 7, 1915. Serial No. 65,510.

To all whom it may concern:

Be it known that I, GUSTAF HJALMAR LINDSTRÖM, a subject of the King of Sweden, and resident of Engelbrektsgatan 38, Gottenborg, in the Kingdom of Sweden, have invented certain new and useful Improvements in Platen Printing-Presses and the like, of which the following is a specification, reference being had therein to the accompanying drawings.

The ink used in printing presses is, as well known, generally tough, owing to which fact the paper forced against the form adheres to the same with a rather great power, so that thin paper sheets can be torn asunder while they are separated from the form. This invention relates to a device adapted specially for automatic platen printing presses for facilitating the separating of the paper sheet from the form, the said device consisting of one or more conduits for compressed air, which conduit supplies an air current into the space between the paper sheet and the printing form, which forces its way between the paper sheet and the form and thus facilitates the separating of the paper sheet. Through the provision of a deflector at the mouth of the said conduit, the air current can be brought to pass either in the said direction, while the paper sheet is separated from the form, or, while the paper sheet is moved to the platen, to pass in such direction, that the air subjects the paper sheet to a slight stretching operation and prevents the sheet from being folded.

In the accompanying drawings a platen printing press provided with a paper sheet separating device arranged in accordance with this invention is shown, in Figure 1 in a side view and in Fig. 2 in a plan view. Fig. 3 shows a detail. Only such parts of the press are shown as are necessary for the explaining of the invention.

The invention is shown applied to a platen printing press, in which the paper sheets are moved automatically to the form and from the same. 1 is the form support, 2 is the collection of types or the so called printing form, mounted on the said support, and 3 is the platen carried by two arms 6 swingable around pins 4 fixed in the frame 5 of the press. The said platen 3 is moved toward and from the form by two links 7 pivoted to the platen and connected with crank disks 8, provided with cogs. The disks 8 are fixed to a common shaft 9 and are rotated by pinions 10 on the driving shaft 11 of the press. When the platen 3 has been moved from the form 2, a transporter, carried by two swingable arms 12 (one only shown in the drawings), is moved to the paper piles on the feed tables 13 and carries with itself the top paper sheets during its return stroke, which sheets are then placed on the platen 3 and engaged by grippers provided on the same. As the said transporter and grippers may be of any suitable construction and form no part of this invention they are not closer described. The platen together with the paper sheets are then moved to the printing form. When the printing operation has been effected, the platen is returned accompanied by the paper sheets. a, Fig. 1, designates a paper sheet. For facilitating the separating of the paper sheets respectively from the printing form the mouth of a conduit for compressed air is, according to this invention, located at the edge of the form, at which the separating of the paper sheet is started during the return stroke of the platen, from which mouth an air current is forced between the paper sheet and the form. According to the drawings the compressed air is supplied by a fan 14 and passes through a pipe 15, provided at its end with a wide mouth piece 16, which extends to the vicinity of the top edge of the printing form and may have such a direction, that the air, supplied by the fan, is forced as a broad current into the space between the paper sheet, partially separated from the printing form, and the said form and in this manner separates or assists in separating the paper sheet from the form. If the object of the air current only is to separate the paper sheet from the printing form, the curve shaped mouth piece is directed more downward than shown in the drawings. In the drawings the mouth piece 16 has such a direction, that, for causing the air current leaving the mouth piece to pass into the space between the paper sheet and the printing form a deflector is necessary provided at the mouth piece. The said deflector consists of a curved shaped disk 17, the curvature of which corresponds to the curvature of the outer side of the mouth piece 16, bent downwardly, Fig. 2. The

said disk 17 is carried by two arms 18, fixed to a shaft 19 journaled in the frame of the printing press. The length of the arms 18 corresponds substantially to the radius of curvature of the outer side of the mouth piece. To one of the arms 18 a link 20 is pivoted, the other end of which is pivoted to an arm 22, swinging around a pin 21 in the frame. The said arm 22 is acted upon by a spring 23 fixed to the frame of the printing press and forcing a roller 24 on the arm 22 against a cam 25, which is provided on a shaft 26 journaled in the frame. The said shaft 26 is rotated by the shaft 9 by means of a gear 27, 28. During the rotation of the shaft 26 the cam 25 swings the arms 18 downward by means of the arm 22 and the link 20, so that the disk 17 is brought into the position shown in Figs. 1 and 3. In the said position the air current is directed into the space between the paper sheet and the printing form. Consequently, the disk 17 occupies the said position, while the platen is moved from the printing form. During the continued rotation of the shaft 26 the cam 25 is brought out of contact with the roller 24 and permits the spring 23 to swing the disk 17 upward. The end of the mouth piece has such direction, that, when the disk 17 has been moved upward, the air current passing from the mouth piece has a forward and downward direction. The disk occupies its upper position and the air current has the direction just mentioned, while the transporter moves the paper sheets from the table 13 to the platen. The air current is then substantially parallel to the paper sheets, moved upward by the transporter and hanging freely down from the same, and slightly stretches the paper sheets, so that they are prevented from folding or being brought into incorrect position on the platen. Moreover the air current causes the paper sheets to fit more closely to the platen. The force of the air current is controlled by means of a cock 29 provided in the pipe 15. The paper sheets separated from the printing form are seized by a second transporter, carried by two swingable arms 30, and placed upon a table 31. Also the said transporter may be of any known construction and is not closer described, as it forms no part of this invention.

The invention may, evidently, be modified in many respects, without departing from the idea, upon which the invention is based. The invention is shown applied to a printing press for the printing of two sheets simultaneously but may evidently be applied to printing presses provided with only one feed table or more than two tables.

Having now described my invention, what I claim as new and desire to secure by Letters Patent is:

1. In a platen printing press the combination of the form support, the platen and a device, which, while the paper sheet is moved from the printing form, forces air between the paper sheet and the form for facilitating the separating of the paper sheet from the form.
2. In a platen printing press the combination of the form support, the platen, a feed table for the paper sheets to be printed, a transporter or the like, which moves the sheets to the platen, means provided on the platen for holding the sheet during the printing operation, a conduit for compressed air, a deflector provided at the mouth of the said conduit, and means for changing the position of the said deflector, so that the air passes either into the space between the platen and the form, against the sheet, moved by the transporter to the platen, and from the edge of the sheet held by the transporter for preventing the sheet from being folded, or into the space between the sheet and the form for facilitating the separating of the sheet from the form.

In witness whereof, I have hereunto signed my name.

GUSTAF HJALMAR LINDSTRÖM.
